UNITED STATES PATENT OFFICE.

JAMES AYRES, OF KEOKUK, IOWA.

BRIDGE-GUARD.

SPECIFICATION forming part of Letters Patent No. 408,064, dated July 30, 1889.

Application filed May 27, 1889. Serial No. 312,273. (No model.)

To all whom it may concern:

Be it known that I, JAMES AYRES, a citizen of the United States, residing at Keokuk, in the county of Lee and State of Iowa, have 5 invented certain new and useful Improvements in Bridge-Guards, of which the following is a specification.

My invention relates to bridge-guards; and it consists, primarily, in the employment of 10 a flexible guard or gate adapted to be moved by the bridge.

In the drawings, Figure 1 is a perspective view of my improved guard with the bridge in position for use and the guard thrown to 15 one side out of the way; Fig. 2, a similar view, with the bridge open and the guard in position to protect the passage-way; and Figs. 3, 4, 5, and 6 views illustrating certain details.

20 A indicates the bridge proper, adapted to swing horizontally, and B B the piers or abutments.

Upon the piers or abutments are secured 25 uprights C C, which carry at their upper ends the curved supporting track or rail D, as shown in Figs. 1, 2, and 3, and said track extending at right angles across the roadway or passage-way, but high enough above the same as not to interfere with the travel of 30 vehicles, and also extending along one side of the pier, so as to be readily supported by the uprights on the pier.

It is not necessary to extend the track around the side of the abutment, as shown, 35 as it may extend in a line parallel with the front face of the latter.

Mounted upon the track or rail D is a flexible guard or gate E, which is composed of a series of connected sections F, of the form 40 represented in Fig. 6. Each section F is composed of an upright rod a, an upper cross-bar b, a lower cross-bar c, and an intermediate cross-bar d. The cross-bars b, c, and d are provided at one end with a perforated lug or 45 tongue e and at the opposite end with perforated ears f, and when the lugs of one section are inserted between the ears of the adjacent section and connected by pins or bolts g, as shown in Figs. 1 and 2, the sections will 50 be found to be flexibly but securely fastened together.

Secured to the upper end of the rod or bar a is a grooved wheel h, to run on the upper edge of the track, while on the same face of the rod or bar is a second wheel i, adapted to 55 run on the lower edge of the track.

In order to keep the gate or guard as a whole away from the outer face of the track or rail, the upper cross-bar will advisably be provided with wheels or rollers j, to run 60 against or in contact with the rail. The intermediate cross-bar d will ordinarily be placed five feet (more or less) from the lower end of the guard, and a single rod or bolt g employed to connect the cross-bars c d of adjacent sections, thus making it practically 65 impossible for children to get through the guard or gate.

The sections F may be made more or less ornamental in appearance, as desired, and it 70 is likewise obvious that the form of hinge or connection between the sections and the arrangement of the friction and supporting wheels are matters that may be varied without in any way departing from the spirit of 75 my invention.

Each section F may be provided with the friction-wheels and the supporting-wheels, or some may be provided with the friction-wheels only and some with the supporting-wheels only, these matters depending upon 80 the circumstances attending the particular gate or guard to be built and other considerations. The lower edge of the guard or gate E will advisably be guided and steadied in 85 its movements by means of wheels or rollers k k, secured in the side wall of the abutment, and a roller or rollers l at the center of the latter, as shown in Figs. 1 and 2.

Hinged or pivoted to the outer face of the 90 gate or guard E at its upper end is a gravitating dog or catch m, which when the gate is in the position shown in Fig. 2 engages with the track or rail D and prevents persons from moving or opening said guard or gate. 95

A stop n on the track or rail is adapted to be engaged by a pin or stud on the guard or gate, so as to limit the movement of the latter in closing, while a stop at the opposite end of the track is adapted to limit the movement of the guard in opening. 100

In order to operate the gate, I mount upon

the bridge an upright (or uprights) G, which has at its upper end an inclined arm q, which is arranged in such manner that as the bridge is swung around to closed position this arm 5 will strike against the horizontal arm r of the latch or dog and cause the latter to ride up the inclined face of said arm q, thereby raising the latch out of engagement with the track or rail.

10 As the bridge continues its movement, an arm or lug s on the face of the upright next to the track or rail comes into engagement with the end of the gate or guard and carries the same back out of the way, as shown in 15 Fig. 1.

Projecting from one edge of the upright G is a hook t, which is adapted to engage with a hook or lug u on the end of the guard or gate E the arrangement of the hooks being such that 20 when the bridge is being opened it will, almost the instant it begins to move, carry the guard or gate with it. As soon as the gate reaches the limit of its movement, the hook t will ride out of engagement with the hook u, 25 thereby allowing the bridge to continue its movement.

While in the drawings I have shown the gate or guard applied to only one end of the bridge or to one abutment, I wish it distinctly 30 understood that I do not limit myself to one only, as it is obvious that the perfect guarding of the approaches to the bridge can only be secured by the use of two guards or gates—one at each end of the bridge.

35 If desired, the track or rail may be incased to protect it from snow and ice, which would interfere with the perfect running of the guard; but as this idea is old and well known I have not considered it necessary to illustrate it.

It will be noted that there are no tracks or guiding-rails on the road-bed, the latter being left smooth and unobstructed.

From the foregoing description it will be 45 noted that there is absolutely no chance for the roadway or passage-way being left unprotected, for the guard or gate is actuated positively in both directions and is drawn across the roadway at the instant the bridge 50 begins to move out of position. It will also be noted that the operation of the guard or gate is automatic, all of the movements of the latter being effected through the bridge, and as the guard is light but little additional 55 power is required to operate it.

The details may be varied both as to the construction of the gate and its supports, and also as to the means for automatically connecting and disconnecting the bridge and gate, 60 without departing from the principle of the invention.

The ends of the bridge and face of the abutment are curved on the arc of a circle, and that portion of the track or rail over the road- 65 way is also curved correspondingly; but it will be observed that the end of the track is

made straight for a short distance, so as to facilitate the disconnection of the hooks or projections t and u, which begin to separate at the moment the guard enters upon the 70 straight part of the track.

While the guard or gate herein shown is designed particularly for use in connection with a bridge, it is obvious that it is capable of application to other uses.

Having thus described my invention, what I claim is—

1. In combination with a bridge and its abutment, an elevated track or rail located upon the abutment, a flexible guard suspended from the track, and a locking device carried by the guard and adapted to engage the rail, all substantially as shown.

2. In combination with a bridge and its abutment, a track or rail secured in position 85 upon the latter, a flexible gate or guard mounted upon the track and provided with a hook or projection, as u, and a hook or projection, as t, carried by the bridge, said parts being arranged in such manner that when 90 the guard has reached the limit of its movement its hook or projection will be in such position as to permit the ready disengagement of the projection on the bridge.

3. In combination with a bridge and its 95 abutment, curved as shown, a track or rail curved correspondingly and provided with a straight portion, and a flexible guard mounted thereon and provided with a hook or projection to be engaged by a projection upon the 100 bridge.

4. In combination with a bridge and its abutment, a flexible guard or gate provided at one end with a projection, as u, and hooks or projections s and t, secured to the bridge, 105 one of said projections t being adapted to engage the guard's lug u when the bridge is being opened, and the other lug s serving to return the guard to its position.

5. In combination with the abutment and 110 the track or rail thereon, a flexible guard or gate mounted upon the track, an automatic locking-dog, a bridge provided with an upright, an inclined arm q carried by the upright, and projections s t, also carried by the 115 upright to engage the guard.

6. In combination with the abutment, the track or rail D thereon, flexible guard or gate E, provided with wheels h to run on the track, a guide-roller to steady the lower edge of the 120 guard or gate, and a bridge adapted and arranged to actuate the guard.

7. A flexible guard composed of a series of hinged sections F, comprising upright rod or bar a, upper, lower, and intermediate cross-bars b, c, and d, perforated at their ends, as shown, and bolts or pins pivotally connecting the cross-bars of adjacent sections.

8. A flexible guard or gate for bridges and the like, comprising a series of connected sections F, each section being composed of an upright rod a, wheels h and i to run on the up- 130

per and lower edges of the track to which the guard is applied, and a friction wheel or wheels *j*.

9. A flexible guard for bridges, &c., comprising a series of sections having upright *a* and cross-bars *b c d*, a pin connecting the cross-bars *b* of adjacent sections, a pin connecting the cross-bars *c d* of adjacent sec-

tions, and a supporting-wheel at the upper end of one of the sections.

In witness whereof I hereunto set my hand in the presence of two witnesses.

JAMES AYRES.
